No. 36,613.

Patented November 3, 1903.

UNITED STATES PATENT OFFICE.

CHARLES ROSS BOAS, OF HARRISBURG, PENNSYLVANIA.

DESIGN FOR A SPOON.

SPECIFICATION forming part of Design No. 36,613, dated November 3, 1903.

Application filed October 3, 1903. Serial No. 175,700. Term of patent 14 years.

To all whom it may concern:

Be it known that I, CHARLES ROSS BOAS, a citizen of the United States, residing at Harrisburg, in the county of Dauphin and State of Pennsylvania, have invented a new, original, and ornamental Design for Spoons, of which the following is a specification, reference being had to the accompanying drawings, in which—

Figure 1 is a plan view of the obverse side of the spoon. Fig. 2 is a similar view of the reverse side.

What I claim as new, and desire to secure by Letters Patent, is—

The ornamental design for a spoon as shown. 15

In testimony whereof I hereby sign my name to this specification, in the presence of two subscribing witnesses, this 28th day of September, 1903.

CHARLES ROSS BOAS.
